FIG. 5.

UNITED STATES PATENT OFFICE.

WILLIAM FRIEDMAN, OF NEW YORK, N. Y.

TOILET ARTICLE.

Application filed February 12, 1926. Serial No. 87,812.

The objects of this invention are to provide a toilet article utilizing strips of individual make-up units; to provide a case wherein the said strip of make-up units may be removably carried and replaceable when the units are used up; to provide means for preventing the make-up units from coming in contact with or disfiguring said case; to enable the case to be opened wide without discharging said make-up units; to permit said make-up units to be in one or more rows; to enable the base portion of the make-up units to be removed after the units have been torn away so that a new set of units may be inserted; to provide for display of printed matter on the strip of units being visible even while the case is closed; to secure simplicity of construction and use; and to obtain other advantages and results as may be brought out in the following description.

Referring to the accompanying drawing in which like numerals of reference indicate similar parts throughout the several views:

Figure 1 is a perspective view of one construction of case used in connection with my invention;

Figure 2 is a transverse section of the case in use;

Figure 3 is a transverse sectional view of a modified construction of case in use;

Figure 4 is a transverse sectional view of a still further modified construction;

Figure 5 is a face view of the inside of one cover section of Figure 4 with the strip of make-up units positioned therein; and

Figure 6 is an edge view of a still further modified construction.

In the specific embodiment of the invention illustrated in said drawing, reference numeral 1 indicates in general a case having a base portion 2 and cover sections 3, 3. The base is constructed as a suitable elongated pocket 4, for receiving the base portion of a filler 5 preferably including a strip 6 of make-up units 7, said units projecting upwardly from the base so as to be included between covers 3, 3 when the same are closed. The strip and make-up units are

preferably integral and of cardboard or some other material easily torn and yet having strength enough to enable the units to be used when torn off. In use, the units are torn out one at a time for individual application, and are then thrown away, and when the whole series of units have been thus used

the remaining portion of the filler from which the units have been torn will be taken from the base 2 of the case 1, and a new filler inserted.

As shown more particularly in Figures 1 and 2, the covers 3, 3 are hinged to the upper edge of the base, and the middle portion of the base may be cut away, if so desired, as at 8, which will result in exposing the base of the filler to view so that printed matter thereon, such as the trade name of the filler, may be seen even while the covers 3, 3 are closed. The upper edge of the covers 3, 3 may be suitably shaped to interlock for holding the same closed except when the article is in use.

Each make-up unit preferably has a tip 9 of a suitable toilet accessory, such as lipstick, rouge, perfume and so forth. In order to prevent this tip from engaging the cover of the case, the strip 6 preferably has a guard 10 attached on each side thereof, said guard extending opposite the tips and interposed between the same and the covers. An appropriate spacer, 11 is inserted between the strip 6 of units 7 and said spacer under normal conditions likewise will prevent the guard from engaging the tip. The tip therefore not only retains its given shape and appearance, but the entire article when opened is neat and attractive and ready to use.

While I have indicated above that the covers are hinged to the upper edge of the base of the case, this part of the description is for the purpose of being definite and not intended to be restrictive of the invention. The covers may be hinged elsewhere than at the top of the base, and as illustrating this difference, covers 12, 12 are shown in

Figure 3 which are hinged to the bottom of a base 13, the base being included between the covers when the covers are closed. Furthermore, the use of guards such as described in connection with Figure 2 may be varied, one such variation being illustrated in said Figure 3 wherein the filler, 14 provides a strip of make-up units 15 which do not have any guard or separator between them and the cover. However, the tips 16 of said make-up units are prevented from engaging the cover by a spacer 17 which in this instance comprises an inwardly bent beading or rib shown in this figure as an integral part of the cover. This beading extends in a direction flatwise of the strip

and transverse to the several units so it will engage the several units 15 of the strip below the tips 16 and space the said tips away from the cover and accordingly constituting 5 a spacer equivalent to the spacer shown in Figure 2. In this same view, furthermore, I have shown that it is within the scope of the invention to include more than one row of make-up units, and for illustrative purposes have included two rows or strips of units 15. The tips of the units of the two rows are held from each other by one or more spacers 18 which preferably are attached to the strips between the same and 10 extend substantially to the tips 16.

As a further modification it is within the scope of my invention to provide a hollowed out portion in the covers opposite the make-up tips so as to prevent said tips from contacting with said covers. Illustrative of this feature of my invention, I have shown a case in Figures 4 and 5 similar to that described in connection with Figure 3, said case in this instance having covers 19, 19 15 hinged to a base 20 for filler 21 having units 22 with tips 23. The covers each have a transverse outwardly directed bead or hollowed out portion 24, which, when the covers are closed, will be opposite to the tips 23 and the body of the cover will therefore engage the stems of the units below the tips and the tips will be prevented from engaging the covers.

Should it be found desirable to discharge 35 the remaining portion of the filler from the bottom of the case after the units have been all torn out, the side walls of the base may be hinged for that purpose. Such a construction is shown in Figure 6, wherein the 40 end wall 25 of the base is fixed with respect to hinges 26, 26, said hinges in the present showing, mounting both covers 27, 27 and base side walls 28, 28. The covers may be 45 swung outward to gain access to the units within, and the base side walls may also be swung outward, as shown in dotted lines, at which time the filler base may be withdrawn.

Obviously other detail changes and modifications may be made in the construction 50 and use of my improved toilet article, and I do not wish to be understood as limiting myself to the exact structure shown except as set forth in the following claims when construed in the light of the prior art.

Having thus described my invention, I claim:

1. A toilet article comprising a base having an elongated pocket for reception of the base of a filler, and covers hinged to said base adapted to close together and enclose said filler therein.

2. A toilet article comprising a base having an elongated pocket for reception of the base of a filler, and covers hinged to the bottom of said base of the article adapted to close together and enclose said base and filler.

3. In a toilet article the combination with a filler having tipped units of a case therefor having covers, and means for preventing the tips from contacting with said covers.

4. A toilet article case for strips of tipped units, comprising means for mounting said units in the case, a hinged cover for said case, and means for retaining the tips out of contact with the said cover.

5. A toilet article case for strips of tipped units, comprising means for mounting said units in the case, and a spacer for retaining the tips of the units out of contact from the walls of the case.

6. A toilet article case for strips of tipped units, comprising means for mounting said units in the case, and a bead in the wall of the case transverse to the units for preventing contact of the said tips with the wall.

7. A toilet article case for strips of tipped units, comprising means for mounting said units in the case, and an inwardly directed bead in the wall of the case transverse to the units below the tips for preventing contact of said tips with the wall.

WILLIAM FRIEDMAN.
